(57) **CLAIM**

I claim the ornamental design for a safety hand rail, as shown and described.

DESCRIPTION

FIG. 1 is a perspective view of a safety hand rail showing my new design;

FIG. 2 is an end elevational view thereof, the elevational view of the opposing end being identical thereto;

FIG. 3 is a top plan view thereof;

FIG. 4 is a side elevational view thereof, the elevational view of the opposing side being identical thereto;

FIG. 5 is a bottom plan view thereof; and,

FIG. 6 is a perspective view showing the safety hand rail in use; the broken lines depict environmental structure for illustrative purposes only and form no part of the claimed design.
